O. WAUHOB

MANIFOLD HEATER

Filed Oct. 29, 1925

By *Orvil Wauhob*
Blair Diamond & Littell

UNITED STATES PATENT OFFICE.

ORVIL WAUHOB, OF SIOUX CITY, IOWA.

MANIFOLD HEATER.

Application filed October 29, 1925. Serial No. 65,627.

My invention relates to a vehicle heater of the type which receives heat from the exhaust manifold and transfers it to the car, and it is my object to provide such a heater which is so constructed that it may be applied either to the ordinary type of manifold used on a Ford car, or to a special type of manifold in which the intake and exhaust manifolds are combined into a single casting, which occupies a lower position relative to the engine than the ordinary manifold.

A further object is to provide such a heater which is formed in two sections, one a channel-shaped casing adapted to enclose the manifold, and the other a short pipe adapted to be extended through the floor boards of the vehicle and to communicate with the casing in such a manner that the upper portion of the exhaust pipe and the adjacent portion of the manifold will be completely enclosed between the two heater sections.

A further object is to provide the above mentioned casing, which is so shaped as to completely enclose both the intake and exhaust manifolds, and is provided with flanges adapted to engage the side face of the engine block to form an enclosed air passage in either of the two vertically separated positions wherein it is applied to the two different types of manifolds.

Another object is to provide attaching means for connecting the casing to the manifold clamp bolts where the casing is applied to the ordinary type manifold, said means being removable where the casing is used with the other type of manifold, above mentioned.

Another object is to provide a pipe section, as above mentioned, which is particularly adapted to connect with the casing when attached to either type of manifold and to form a substantially continuous air passage in connection therewith.

With these and other objects in view, my invention consists in the construction, arrangement and combination of the various parts of my device, whereby the objects contemplated are attained, as hereinafter more fully set forth, pointed out in my claim and illustrated in the accompanying drawings, in which:

Fig. 1 is a side elevation of the heater applied to the ordinary type manifold, parts

being shown in section and parts being broken away to better illustrate the construction.

Fig. 2 is a side elevation of the heater applied to a combined intake and exhaust manifold.

Fig. 3 is a plan view of the heater in its latter mentioned application.

Fig. 4 is an inverted plan of the casing.

Fig. 5 is a detail sectional view taken on the line 5—5 of Fig. 2, and

Fig. 6 is a detail sectional view taken on the line 6—6 of Fig. 1.

In providing a heater adapted to be applied to either of the above mentioned types of manifold for a Ford car, several problems are encountered. It is first necessary to provide an enclosed air passage in which there are as few as possible apertures from which the air may escape while traveling through the heater. In old types of exhaust heaters this has been accomplished by forming the air passage between the top of the exhaust manifold and the casing which goes over the manifold, and sealing the side of the casing against the vertical side of the ordinary manifold, shown at 10 in Fig. 6, in cross section. The manifold has the discharge ports, 11, which communicate with the side of the engine block, 12, which is enlarged at the head thereof as illustrated and consequently cut away below the head.

The combined intake and exhaust manifold, which is of a common type now in use, is shown in cross section in Fig. 5, the intake portion of the manifold being indicated at 13 and the exhaust portion at 14.

It will be noted that the combined manifold is relatively much wider than the ordinary type manifold and for this reason it is impossible to utilize the ordinary type of heater casing for application to such a manifold.

The contour of the combined manifold is also so irregular that it is impractical to attempt to utilize the manifold as a part of the air passage. This is primarily due to the projecting intake portion which occupies only a portion of the length of the manifold, as is indicated in dotted lines in Fig. 3. I therefore provide a casing which will entirely enclose the manifold and which is constructed with an open side to receive the manifold, which will be closed by the side

of the engine block. The casing is therefore made with a side wall, 15, an upper wall, 16, and a lower wall, 17, which is slotted as at 18 to receive the fuel passage, 19, of the 5 combined manifold, and slotted as at 20 to receive the fuel passage, 21, of the ordinary intake manifold.

It will be noted from a comparison of Figs. 1 and 2, which show the relative position of the two types of manifold, that the casing must be dropped to a position considerably below that of its position around the ordinary manifold to receive the combined type. In so positioning the casing the 15 lower wall, 17, will be dropped below the shoulder of the enlarged portion of the engine block, 12, and I therefore provide an upturned flange, 22, formed on the bottom wall, 17, and having a slot, 23, forming a 20 continuation of the slot, 18, shown in Fig. 1 in dotted lines. The upper wall, 16, is also provided with a downwardly turned flange, 24, which serves to close the air passage when the casing is applied to the ordinary 25 type manifold.

As seen in Fig. 5, when the casing is applied in its lowered position, the flange, 22, will extend upwardly to meet the shoulder of the engine block, 12, and enclose the air 30 passage. When the casing is in its upper position the flange, 24, will extend downwardly for the same purpose, as shown in Fig. 6.

In this connection it will be noted that the 35 highest portion of the exhaust manifold, 10, is somewhat above the upper lever of the engine block, and the upper wall, 16, is thus positioned slightly above the engine block when the casing is installed as in Fig. 1.

40 The casing is provided with an opening, 25, which receives a protruding portion, 26, of the combined manifold, so that the casing may rest snugly against the face of the intake portion, 13.

45 An opening, 27, in the upper wall, 16, of the casing received a bolt, 28, which is customarily provided with this type of the manifold for the purpose of pivoting a control lever for a special type of carburetor. 50 If this control lever is used it may be attached above the wall, 16, and will assume its ordinary position. However, the manifold is customarily used with the ordinary type carburetor, and the bolt, 28, thus serves 55 the purpose of attaching my heater to the manifold, as shown in Figs. 2 and 3.

When the heater is applied to the ordinary type manifold, a bracket, 29, is secured to the upper wall of the heater by means of 60 a bolt, 30, received through the opening, 27. A bracket, 31, is similarly secured to the wall, 16, of the casing near the forward end thereof. Each bracket is substantially L-shaped and extends downwardly to position 65 to receive the manifold clamp bolts, 32, the

70 nuts of which are removed in order that the brackets, 29 and 31, may be secured in place. The brackets are ordinarily secured first to the bolts, 32, and the casing then secured to the brackets.

75 In order that access may be had to the interior of the casing to attach the bolt, 30, the opening, 25, is properly located for this purpose.

When the casing is used with the ordinary type manifold, the opening, 25, is closed with a cover, 33, pivoted at 34, to the casing. The cover, 33, has a hook, 35, shown 80 in Fig. 6, which engages the corner of the casing to secure the cover in its closed position, shown in Fig. 1. When the cover is in open position, it is swung outwardly to allow the hook, 35, to ride past the side wall, 15, and the hook, 35, is then received in a slot, 36, shown in Fig. 1.

85 The rear end of the side wall, 15, is cut at an angle, as shown at 37 in Fig. 2, the angle being substantially that normally assumed by the exhaust pipe when connected to the manifold.

90 It will now be seen that the casing will project beyond the engine block and will enclose a space by its outer side substantially to the center of the exhaust pipe, 38, whether applied to either type of manifold. 95 This is due to the fact that the exhaust pipe has a position relative to the combined type manifold substantially as much lower than that of the position relative to the ordinary type as the difference in the positions assumed by the casing of the heater. The inner side of the air passage, however, will be left open beyond the extremity of the 100 engine block.

105 I therefore provide a heat discharge pipe having the side walls, 39, which are shaped as indicated in dotted lines at 40 in Fig. 1, to extend into the casing as far as possible. The wall, 39, which is next to the engine block will thereby close the air passage on that side. The upper wall, 41, of the discharge pipe has a detached lip, 42, which may be bent upwardly when the heater is attached to the ordinary manifold in order to form a closer union between the pipe and the casing, and to avoid the rear portion of the exhaust manifold, 10.

110 When the heater is applied to the combined type, the lip, 42, assumes the position shown in Fig. 2, and serves to close the pipe for a greater portion of its length in order that the casing may be lowered relative to the pipe without disclosing a gap between the two.

115 The lower wall, 43, of the pipe is slotted to receive the exhaust pipe and the lower wall, 17, of the casing is likewise slotted, as at 44, a lip of metal, 45, being allowed to remain which may be shaped to the under 120 side of the pipe to conform to the slight 125

variation of position of the lower wall of the casing relative to the pipe as between its two positions.

The lower wall, 43, is likewise provided with a lip, 46, formed by the slot therein, which is similarly shaped to the exhaust pipe to provide for the difference in their relative position.

A slot, 47, is provided in the upper wall 10 and a slot, 48, in the lower wall of the casing to receive the ordinary carburetor control fork.

Some changes may be made in the construction and arrangement of the parts of 15 my invention without departing from the real spirit and purpose of my invention, and it is my intention to cover by my claims any modified forms of structure or use of 20 mechanical equivalents which may be reasonably included within their scope.

I claim as my invention:

In a manifold heater, a casing member having an outer side wall and having up-

per and lower walls adapted to bear against the side of an engine block and to form 25 therewith an enclosed air passage in either of two vertically spaced positions, and a delivery pipe having an upper wall provided with a partially detached portion, said delivery pipe being receivable between the 30 outer wall of the casing and the side of the engine block, and said partially detached portion being bendable upwardly to close a gap existing between the upper wall of the casing and the upper wall of the delivery 35 pipe when the casing is in its upper position, said partially detached portion being also bendable to conform with the upper wall of a manifold when the casing is in its lower position on a different type of 40 manifold.

Signed at Sioux City, in the county of Woodbury and State of Iowa, this 27th day of October, 1925.

ORVIL WAUHOB.
